Re. 21,357

PRODUCTION OF SO₂ FROM ACID SLUDGE

Original Filed Dec. 2, 1933

UNITED STATES PATENT OFFICE

21,357

PRODUCTION OF SO₂ FROM ACID SLUDGE

Frank J. Bartholomew, Westfield, N. J., assignor
to Chemical Construction Corporation, New
York, N. Y., a corporation of Delaware

Original No. 2,028,713, dated January 21, 1936,
Serial No. 700,757, December 2, 1933. Application
for reissue September 9, 1938, Serial No.
229,149

15 Claims. (Cl. 23—177)

This invention relates to the production of SO₂ from acid sludge and more particularly from the acid sludge obtained in the sulphuric acid purification of petroleum hydrocarbons.

5 In the past acid sludge obtained in oil refineries has presented a serious problem. Many attempts were made to decompose the sludge thermally with the production of a gas containing SO₂. The attempts did not prove commercial successes until in 1931 the Hechenbleikner process, described and claimed in the co-pending application of I. Hechenbleikner, Serial No. 568,050, filed October 10, 1931, now Patent Number 1,953,225, was developed using an internally 10 heated rotary kiln. This process achieved immediate commercial success producing an SO₂ gas free from H₂S and SO₃ and leaving a residue in the form of a coke-like fuel which was continuously removed from the kiln.

20 The main use for the SO₂ gases from the decomposition of acid sludge is to reoxidize them to SO₃ in order to produce sulphuric acid for the oil refinery. When used in the contact process or even in the chamber process the presence of 25 hydrocarbons in any considerable amount is very injurious. Unfortunately the gas obtained from the Hechenbleikner kiln, besides water and condensable hydrocarbons, contains a considerable proportion of uncondensable hydrocarbons and 30 also some of the condensable hydrocarbons tend to form an oil mist which cannot be completely removed in the ordinary condensers. It became necessary to remove hydrocarbons in the Hechenbleikner process and this was effected practically by burning them out. This method while satisfactorily removing the hydrocarbons which would have otherwise been transformed into water in the contact plant with concomitant formation of the acid mist, diluted the gases very 35 materially. In sludges which are low in oil the amount of hydrocarbons was not sufficiently great so that excessive dilution resulted from burning them out. On sludges of this type, therefore, the straight Hechenbleikner process operates with excellent commercial efficiency. 40 When, however, high oil sludges are to be treated it became necessary to remove a part of the oil which was achieved by distilling off the more volatile hydrocarbons at low temperature, which left a sludge having the characteristics of low oil sludges and which could be satisfactorily handled in a straight Hechenbleikner process. This modification of the Hechenbleikner process is described and claimed in my co-pending application Serial No. 679,023, filed July 5, 1933. This

application is now Patent No. 2,049,243 dated July 28, 1937.

I have found that the difficulties involved in the decomposition of high oil sludges are completely obviated when, instead of using combustion gases as a heating medium, finely divided heated solids, such as hot sand, are employed. When hot sand is contacted with an acid sludge in a closed vessel such as a kiln, decomposition takes place extremely rapidly permitting great 10 capacity from small apparatus and producing a very strong gas which may contain from 75 to 90% SO₂. The coke and sand which are discharged from the kiln in the present process form a more or less homogeneous mass and when 15 burned in a suitable furnace or kiln the sand is heated by the combustion of the coke and is reused to decompose further amounts of sludge. The gas which is evolved, when cooled to condense out water and condensable hydrocarbons, 20 has so low a hydrocarbon content as compared to SO₂ that the hydrocarbons can be burned out without any dilution problem and in some cases it is not necessary to remove them at all as where the hydrogen content is sufficiently low so that 25 after mixing enough air to bring the SO₂ to the proper concentration for use in the contact process, the hydrogen content is not more than 3 milligrams per cubic foot. While this complete 30 elimination of hydrocarbon removal is only possible with certain sludges, in every case the removal of hydrocarbons is simplified and the bad results from excessive dilution are not experienced.

The very strong SO₂ gas likewise lends itself to other utilization. Thus, for example, a very efficient purification can be effected by absorbing the SO₂ in water or dilute SO₂ liquor and then stripping the SO₂ off from the liquor either by heat or by bubbling air through it. Another outlet lies in the production of liquid SO₂ which can be made effectively from the high strength gas by compression and cooling. The present invention also lends itself to the production of sulphur from the SO₂ gases, for example, by the process described and claimed in the co-pending application of C. B. Clark, Serial No. 675,973, filed June 15, 1933. A continuation in part containing the disclosure of this application was filed on April 45 15, 1938, as Serial No. 202,143, and the original application has become abandoned. The greater 50 the strength of SO₂ gas the more efficient is the process and this is particularly true in the sulphur recovery apparatus which cannot function 55

effectively unless the concentration is kept reasonably high.

The present process is very economical because the coke in many cases has a very low sale value, if it has any at all, by reason of the fact that most refineries are not situated near a market for this type of fuel. The present invention utilizes this coke most effectively in running the process as there are more than enough heat units in the coke produced to reheat the sand. A further advantage lies in the fact that the sand, by reason of its very large surface, reacts with the acid sludge at an extraordinarily high rate of speed so that relatively small kilns can be used, which greatly reduces the apparatus cost for a given installation. Similarly the highly concentrated SO_2 gas requires much smaller purification equipment than is the case in a straight Hechenbleikner process where large volumes of diluting gases must be handled.

The amount of sand required, of course, depends to some extent on the sludge and on the temperature to which the sand is heated. I have found that very satisfactory results are obtained when the weight of sand is from three to four times that of the sludge and the temperature of the sand entering the kiln may advantageously be in the neighborhood of 1500° F. , although the invention is in no sense limited to any such temperatures or proportions. Where the amount of coke is greater than that needed to heat the sand it may be burned with a sufficient excess of air to keep the temperature of the sand down to the desired figure. In general the temperature conditions will vary with different sludges, but it is an advantage of the present invention that it can be used with practically any sludge and requires virtually no modification of apparatus for different sludges. This is of great importance where the plant may have to handle sludges of different compositions and consistencies.

The invention will be described in greater detail in conjunction with the drawing which shows in diagrammatic elevation, partly in section, a typical installation embodying the present invention. It should be understood, of course, that the particular apparatus shown in no sense limits the invention, but is merely a representative example of the type of equipment in which the present invention may be practiced.

In the drawing the sludge decomposition kiln is shown at 1, it being noted that the kiln is very much smaller than a kiln of comparable capacity in a straight Hechenbleikner process. In fact the kiln is approximately one-quarter as long as is needed in the standard Hechenbleikner process. Hot sand at about 1500° F. is fed into the kiln by means of the screw 2 and at the same time sludge is pumped from the tank 3 by means of the pump 4 into the kiln where it mixes with hot sand as the kiln revolves. If desired, the sludge inlet pipe may be water cooled to prevent plugging because of coke formation in the pipe. The proportion by weight of sand to sludge may vary with different sludges. I find that very satisfactory results are obtained when the proportion is from 3 of sand to 1 of sludge to 4 of sand to 1 of sludge, but other proportions may be used. The decomposition of the sludge takes place very rapidly and a fine mixture of sand and coke is produced which is discharged at about 400° F. through the coke discharge 6. The gases evolved

pass out through gas outlet 5. The sand and coke mixture falls on to a conveyor 7 on which it is transported to elevator 8 which raises it and discharges it into heating kiln 9 where the coke is ignited by the pilot flame 21 and burns. The combustion gases pass up the stack 10. The combustion of the coke intimately mixed with the sand heats the latter to red heat and the sand is then discharged through the valve 11 into the screw feed where it flows into the kiln. The screw does not extend to the opening into the kiln so that sand piles up and acts as a gas seal. The hot gases passing out through the stack 10 may, of course, be utilized in any suitable manner such as in a waste heat boiler (not shown).

The gases evolved from the decomposition of the sludge pass through a baffled air condenser 12, thence through a condenser coil 13, cooled by a spray of water from the spray 14, and finally through a scrubbing tower 15 in which a constant circulation of water is effected by the pump 16. Fresh water is introduced into the system through the valved pipe 17. In the condensers and scrubbing tower hydrocarbons are very effectively condensed since the gases are undiluted by combustion gases and accordingly there is little or no oil mist formation. The water, which of course is saturated with SO_2 , and the condensed oils flow out from the bottom of the two condensers through the pipe 18 into the separator 19 where oil is drawn off through the pipe 20 and the water containing dissolved SO_2 is continuously removed through a siphon pipe and, if desired, the SO_2 content may be recovered by stripping, preferably by means of heat. SO_2 solution and oil which is formed in the scrubber 15, are continuously drawn off from the circuit through a valved pipe which connects to the pipe 18.

The scrubbed gases leaving the tower 15 through the pipe 22, flow up through an absorbing tower 23 counter to a spray of cold water or dilute SO_2 solution. Practically all of the SO_2 is absorbed, the small residue of fixed gases being sucked off from the top of the tower by the blower 24. The SO_2 liquor thus formed flows out of the bottom of the tower through the pipe 25 into an SO_2 liquor tank 26. From the tank 26 the SO_2 liquor is pumped by the pump 27 into the top of a stripping tower 28 where it flows down over packing in countercurrent to a stream of air introduced into the bottom of the tower through the air inlet 29. This air strips most of the SO_2 out of the liquor and passes out at the top of the tower through the pipe 30. The stripped liquor flows out of the bottom of the tower through the pipe 31 into the weak liquor tank 32, where, if desired, make-up water may be introduced through the valved pipe 33. Make-up water is required as the amount of water vapor carried off by the blower 24 and by the stream of air in the stripping tower, is greater than the amount of moisture in the gases leaving the scrubber 15.

The SO_2 gas which is mixed with the proper amount of air for conversion into SO_3 by the contact process, leaves the tower 28 in a highly purified form but containing, of course, a considerable amount of moisture. This moisture is removed in the dryer 34 where the gas bubbles through a strong sulfuric acid which may be for instance, of 93% strength. The acid is circulated through the dryer from the acid tank 35 by means of pump 36, a cooler 37 being provided to

5 maintain the temperature at the desired point so as to ensure efficient drying. The dehydrated gases are then sucked by the blower 38 and forced through the converter 39 which consists of a catalyst containing portion 40 and a heat exchanger 41. The converted gases after leaving the heat exchanger through pipe 42 are then absorbed in an absorber 43 in the usual manner, the waste gases passing out through a stack 44.

10 The circulation of acid, which may be of 98% or greater strength, is from the tank 45 through the pump 46, absorber 43, and back through the cooler 47. The absorption of SO_2 in the absorber 43 requires the addition of water to the system. This is normally effected by causing a portion of the weak acid from the dryer circuit to flow into the absorber circuit through the valved pipe 48. Similarly, a portion of the strong acid from the absorber circuit can be

15 caused to flow back into the dryer circuit through the valved pipe 49. Valved draw-off pipes 50 and 51 serve to draw off acid from the tanks 35 and 45 respectively, depending on whether the system is to produce 93% acid or 20 stronger acid. If oleum is to be produced, usually two absorbers are arranged in series.

It should be understood that the particular method of purifying SO_2 gases by means of an absorber and stripper does not limit the invention. It is a very effective method of obtaining SO_2 gas of high purity for the contact process, but any other method may be used which proves desirable under the particular conditions of a given installation. Thus, for example, if it is desired, the small amount of hydrocarbons remaining in the gas leaving the scrubber 15 may be burned out as described in Hechlenbleikner and Mast application above referred to. Of course, the strength of the SO_2 gas is so great 25 that no material dilution troubles arise.

40 The converter, absorber and drying system is shown in purely conventional form, and it should be understood that the invention may be used with any suitable design of converter, dryer or 45 absorption equipment.

45 The invention has been described in detail in conjunction with a utilization of the SO_2 gas involving purification of the SO_2 beyond condensation of water and condensable hydrocarbons. This is not the only method of practicing the invention. Thus, for example, where the plant is situated close to a sulphur burning or sulphide ore burning plant the SO_2 gases from the two plants may be mixed which will normally result in a sufficient dilution of the hydrocarbon content so that the hydrogen present is less than three milligrams per cubic foot, and the mixed gases may be oxidized in a contact sulphuric acid process without further purification. This combined process is not claimed 50 per se in the present application as it forms the subject matter of the co-pending application of C. B. Clark, above referred to.

55 The invention has been described in great detail in conjunction with the treatment of acid sludge from the sulphuric acid purification of petroleum hydrocarbons. It is, of course, equally applicable to the decomposition of any sulphuric acid sludge from the purification of any 60 carbonaceous material, such as, for example, coal tar fractions and the like.

70 When the coked residue and sand is passed through the heating kiln too rapidly for all the coked residue to burn, a mixture of hot coked material and sand is discharged into the sludge

75 kiln and operates as effectively as if pure hot sand were used. Where the amount of coked residue produced is considerably in excess of that required to heat the sand, as is normally the case, this method eliminates the sand from the cycle and substitutes the hot coked material as the heating medium although it does not change any of the essential features of the process. The solid particles of coked material, when mixed with sludge in the decomposition kiln, operate 10 as a heating medium in exactly the same manner as the sand which they replace. A mixture of coked material augmented by coke-like solid carbonaceous residue from the sludge is discharged from this kiln and introduced into the 15 heating kiln where part of the material so introduced is burned to reheat the entire coked material, just as is done with sand.

What I claim is:

1. A method of decomposing acid sludge from the sulfuric acid purification of hydro-carbonaceous material to yield a gas containing SO_2 substantially free from H_2S , which comprises thoroughly mixing the sludge with a stream of highly heated finely divided solid particles, the amount and temperature of the solid particles being sufficient to decompose the sludge and to form a coke-like solid residue in intimate admixture with the finely divided heated particles, continuously removing the SO_2 gas produced 30 from the zone of reaction, removing the carbonaceous residue from the zone of reaction and burning the carbonaceous residue in order to reheat the solid particles contained therein and reusing at least a major portion of the reheated 35 material.

2. A method according to claim 1 in which the heating medium is hot sand.

3. A method of decomposing acid sludge from the sulfuric acid purification of petroleum hydrocarbons, which comprises thoroughly mixing the sludge with a stream of highly heated finely divided solid particles, the temperature and amount of the particles being sufficient to decompose the sludge to a carbonaceous residue 40 without formation of H_2S , continuously removing the SO_2 gas given off from the zone of reaction, removing the carbonaceous residue formed in intimate admixture with the heated particles and burning the residue to reheat the heating 45 particles and reusing at least a major portion of the reheated material.

4. A method of decomposing acid sludge from the sulfuric acid purification of petroleum hydrocarbons, which comprises thoroughly mixing 55 the sludge with a stream of highly heated sand, the temperature and amount of the sand being sufficient to decompose the sludge to a carbonaceous residue without formation of H_2S , continuously removing the SO_2 gas given off from 60 the zone of reaction, removing the carbonaceous residue formed in intimate admixture with the heated sand and burning the residue to reheat the heating sand and reusing at least a 65 major portion of the reheated material.

5. A method according to claim 3 in which the SO_2 gases are cooled to condense water and condensable hydrocarbons, uncondensable hydrocarbons are removed from the gas, the composition of the gas is adjusted to that suitable for oxidation of the SO_2 in the contact sulfuric acid process and the SO_2 is oxidized in contact with a contact sulfuric acid catalyst. 70

6. A method according to claim 3 in which the SO_2 gas is cooled to condense out water and 75

- condensable hydrocarbons, the gas is passed in contact with cold water having a sufficiently low concentration of dissolved SO_2 to substantially absorb the SO_2 of the gas and the SO_2 is removed from the liquor thus produced.
7. A method according to claim 3 in which the SO_2 gas is cooled to remove water and condensable hydrocarbons, the gas is then passed in contact with cold water having a sufficiently small content of dissolved SO_2 so that substantially all of the SO_2 of the gas is absorbed, the SO_2 is stripped from the liquor thus produced by a stream of air to form an SO_2 gas having sufficient concentration for use in the contact sulfuric acid process and the gas is passed thus formed at reaction temperature over a contact sulfuric acid catalyst.
8. A method according to claim 3 in which the SO_2 gas is cooled to remove water and condensable hydrocarbons and is then contacted with cold water having a sufficiently small dissolved SO_2 content so that the SO_2 of the gas is substantially absorbed, the liquor thus formed is stripped by passing air therethrough to form an SO_2 gas of suitable concentration for the contact sulfuric acid process, at least a portion of the stripped liquor is used for absorbing further amounts of SO_2 in the process and the SO_2 gas obtained by the stripping operation is passed at reaction temperature over a contact sulfuric acid catalyst.
9. A method according to claim 4 in which the SO_2 gases are cooled to condense water and condensable hydrocarbons, uncondensable hydrocarbons is removed from the gas, the composition of the gas is adjusted to that suitable for oxidation of the SO_2 in the contact sulfuric acid process and the SO_2 is oxidized in contact with a contact sulfuric acid catalyst.
10. A method according to claim 4 in which the SO_2 gas is cooled to condense out water and condensable hydrocarbons, the gas is passed in contact with cold water having a sufficiently low concentration of dissolved SO_2 to substantially absorb SO_2 of the gas and the SO_2 is removed from the liquor thus produced.
11. A method according to claim 4 in which the SO_2 gas is cooled to remove water and condensable hydrocarbons, the gas is then passed in contact with cold water having a sufficiently small content of dissolved SO_2 so that substantially all of the SO_2 of the gas is absorbed, the SO_2 is stripped from the liquor thus produced by a stream of air to form an SO_2 gas having sufficient concentration for use in the contact sulfuric acid process and the gas thus formed is passed at reaction temperature over a contact sulfuric acid catalyst.
12. A method according to claim 4 in which the SO_2 gas is cooled to remove water and condensable hydrocarbons and is then contacted with cold water having a sufficiently small dissolved SO_2 content so that the SO_2 of the gas is substantially absorbed, the liquor thus formed is stripped by passing air therethrough to form an SO_2 gas of suitable concentration for the contact sulfuric acid process, at least a portion of the stripped liquor is used for absorbing further amounts of SO_2 in the process and the SO_2 gas obtained by the stripping operation is passed at reaction temperature over a contact sulfuric acid catalyst. 5
13. A method according to claim 3 in which the SO_2 gases are cooled to condense water and condensable hydrocarbons, the gases are mixed with sufficient air to produce a gas having a suitable SO_2 concentration for the contact sulfuric acid process, moisture is removed and the hydrocarbon content of the gas is adjusted so that the weight of hydrogen in the hydrocarbon is less than 3 mg. per cubic foot of gas and the gas is passed thus adjusted at reaction temperature over a contact sulfuric acid catalyst. 15 20
14. A method of decomposing acid sludge from the sulfuric acid purification of hydrocarbonaceous material to yield a gas containing SO_2 substantially free from H_2S , which comprises thoroughly mixing the sludge with a stream of highly heated finely divided solid particles in a rotary kiln, the amount and temperature of the solid particles being sufficient to decompose the sludge and to form a coke-like solid residue in intimate admixture with the finely divided heated particles, continuously removing the SO_2 gas produced from the zone of reaction, removing the carbonaceous residue from the rotary kiln and burning the carbonaceous residue in order to reheat the solid particles contained therein and reusing at least a major portion of the reheated material. 25 30 35
15. A method of decomposing acid sludge from the sulfuric acid purification of petroleum hydrocarbons, which comprises thoroughly mixing the sludge with a stream of highly heated solid particles in a rotary kiln, the temperature and amount of the particles being sufficient to decompose the sludge to a carbonaceous residue without formation of H_2S , continuously removing the SO_2 gas given off from the zone of reaction, removing from the rotary kiln the carbonaceous residue formed in intimate admixture with the heated particles and burning the residue to reheat the heating particles and reusing at least a major portion of the reheated material. 40 45 50 55
